(57) CLAIM

I claim the ornamental design for a combined stapler and pencil sharpener, as shown and described.

DESCRIPTION

FIG. 1 is a top perspective view of a combined stapler and pencil sharpener of the present invention;

FIG. 2 is a top view thereof;

FIG. 3 is a first side view thereof;

FIG. 4 is a bottom view thereof;

FIG. 5 is a front view thereof;

FIG. 6 is a rear view thereof; and,

FIG. 7 is a second side view thereof.

1 Claim, 3 Drawing Sheets

FIG. 1

FIG. 2

FIG. 3

FIG. 4

FIG. 5

FIG. 6

FIG. 7
